UNITED STATES PATENT OFFICE.

LESTER M. WALDEN, OF CHICAGO, ILLINOIS, ASSIGNOR TO LANSTON MONOTYPE MACHINE COMPANY, OF PHILADELPHIA, PENNSYLVANIA, A CORPORATION OF VIRGINIA.

RECORD-STRIP COMPOSING-MACHINE.

1,149,232.

Specification of Letters Patent. Patented Aug. 10, 1915.

Application filed November 5, 1914. Serial No. 870,464.

To all whom it may concern:

Be it known that I, LESTER M. WALDEN, a citizen of the United States, residing at Chicago, in the county of Cook and State of Illinois, have invented certain new and useful Improvements in Record-Strip Composing-Machines; and I do hereby declare the following to be a full, clear, and exact description of the same, reference being had to the accompanying drawings, forming part of this specification, and to the figures and letters of reference marked thereon.

This invention relates to improvements in typographic composing machines, wherein each unit of the composed matter is represented by a designating member, such as a finger key, the operation of which produces through appropriate mechanism indicating perforations in a record strip, and the invention has for its principal object the provision of means whereby the mechanism responsive to a designating member when once set in motion, as by the depression of the key, is continued in action, and caused to automatically repeat its function until arrested, either by the release of the key or by automatic means, such as will be hereinafter referred to.

The invention is primarily designed for embodiment in a key board such as that employed in the Lanston monotype system of casting type and producing justified lines, although it is not necessarily limited thereto.

The object of the present invention is to simplify and improve the mechanism for effecting the repeat action as well as to provide a mechanism which may be readily adapted to or incorporated in machines of the standard type now in extensive use without requiring material alteration therein or the addition of expensive or complicated parts.

Inasmuch as the invention has been particularly adapted for and has been practically applied to the standard monotype key board it is for the purpose of the present application shown in connection with such a board, and in order that the general features of construction of the board may be more fully appreciated reference may be had to the patent to Bancroft and Indahl, No. 944,405, dated December 28, 1909, in which a key board is illustrated and described, having substantially all of the essential charac-

teristics of the standard Lanston monotype key board now on the market, and the accompanying drawings will be recognized as illustrating such parts of the machine shown in said patent as are necessary for a complete understanding of the present invention.

In said drawings,—Figure 1 is a side elevation, partly in section and partly broken away, of a key board having the present invention applied thereto. Fig. 2 is a perspective view looking at the base portion of the paper tower and top of the base frame of the key board and illustrating features of the present invention. Fig. 3 is a similar view showing the action of the automatic trip for arresting the operation of the repeat mechanism. Fig. 4 is an elevation, partly in section, looking at the back of the base of the key board with the cover plate removed. Fig. 5 is a perspective view showing a convenient means whereby the repeat mechanism may be thrown into or out of operative relation to the designating mechanism. Fig. 6 is a detail elevation showing the action of the designating member on one of the valve stems in the normal operation of the machine and in dotted lines the action of the repeat mechanism when repeated operations of the indicating mechanism are to be effected.

Like letters of reference in the several figures indicate the same parts.

In the Lanston monotype key board adopted for illustrating the present invention, it will be understood that the selectors or punches for making the indications in the record strip are operated by a motor mechanism usually consisting of cylinders and pistons to which compressed air is admitted by a valve mechanism and the valve mechanism is under the direct control of finger keys or designating members, the operation of any one of which, through appropriate connections, operates the proper valves or valves for admitting air to advance the desired punch or punches. The record strip passes through suitable mechanism whereby it is guided and fed into position to be operated on by the punches and the feeding of the record strip is automatically effected in proper time with the operation of the punches whereby there will be no conflict of the punching and feeding movements. The machine embodies competent mechanism

both for indicating the progress of the composition in given lines of matter, and the justification area which must be filled by proper indications for justifying the line in the casting machine.

5 A description of details of the motor mechanism is unnecessary for a proper and complete understanding of the present invention, and the same is true of the justification indicating and designating mechanism other than such parts as are employed in the automatic arresting of the repeat operation, all as will be hereinafter explained.

10 In said drawings,—the base frame of the key board is indicated at 1 and the paper tower at 2, while one of the many ordinary character designating keys is indicated at 3, said key being adapted to advance a key bar, which, through appropriate connections, advances a valve bar or punch controlling member, such for example, as the valve bars indicated at 173 for operating one of the valve stems 5 to open the valve.

15 In accordance with the well understood construction, a single designating key 3 may operate one or more of the bars for opening valves to advance one or more punches for forming the desired indications in the record strip.

20 30 In order that the machine illustrated may be more readily understood in connection with the Patent No. 944,405, hereinbefore referred to; certain of the parts shown in said patent and in the accompanying drawings are designated by corresponding reference numbers, as for example, the punch bars 15, the shaft 34 which is provided with a bail for coöperation with the punch bars, whereby the shaft will be operated in time 35 with said bars. Said shaft has on its end an arm 152 with a cam slot 153 therein with which coöperates a roller 154 on one end of a valve operating lever 148, whereby valve 146 is shifted to alternately admit compressed air and to permit the same to be exhausted from cylinders 137 and 138. The cylinders 137 and 138 contain pistons for operating the lever 139 to which is connected a rod 141 of the paper feed mechanism.

40 45 50 The paper feed mechanism is of the usual construction and need not be described further than to say that in the particular arrangement illustrated the paper is fed during the upward movement of the rod 141 which movement is effected by the admission of air to the cylinder 137, and retrograde or downward movement of said bar is effected by the upward movement of the piston in cylinder 138. The movements of the valve for admitting air to these cylinders is such that when air is admitted to one cylinder the opposite cylinder is opened to exhaust and vice versa, and by reason of 55 60 65 the cam slot 153 the timing of the valve is

so controlled and regulated that the rod 141 is never moved upwardly to feed the paper at a time when the punches are projected through the record strip.

70 At the front of the machine there is the motor cylinder 4, units wheel 7, justification indicator drum 8, units wheel holding pawl 12 and line scale rack 14, all of which are salient features in the standard monotype key board and are designated as hereinbefore stated by corresponding reference numbers in the said patent.

75 80 85 In accordance with the present invention a motor mechanism is provided which is independent of the motor mechanism found in the standard equipment and which is adapted when set in action to effect a repeated operation of selector mechanism which has been initially operated by the key of the character desired, and this character key, it will be understood, may be a so-called quad, leader, dash or a character of any kind. It is not essential that a punch be operated in connection therewith for under certain circumstances the absence of a punch indication in the record strip will set the casting machine for the production of a desired character, as, for example, when the die case of the casting machine is positioned by a fixed stop or is at the extreme of its 90 movement.

95 Conveniently, the motor mechanism for the repeat devices is a pneumatic cylinder which receives its motive fluid under the control of a valve, such, for example, as the valve 146, so as to operate in timed relation to the selector mechanism and effect an intermittent movement of the piston in the motor cylinder, and the movement of this piston is made effective for releasing and again advancing the valve stem of the valve which has been operated by the designating key, but it will be understood that motor-mechanism of the character referred to may be arranged to effect the operation of any 100 part of the chain of connections between the key and the selector mechanism for the record strip, and that its operation will be continued so long as the key is held in its operated position, provision being made, 105 whereby the repeat mechanism may be thrown into and out of operation at will, through the manipulation of a separate control device, such as a repeat key, thus making the machine competent for operation 110 in the ordinary way, where no repeat action is desired, or for repeating the indication produced in the record strip.

115 120 125 Provision is also made whereby the repeat controller or key may be temporarily locked in its operated position and automatically released by the operation of mechanism found in the machine, when the line has been filled or the desired number of repeat characters have been indicated in the record 130

strip. This automatic arresting of the repeat action is preferably controlled through the line scale rack which progresses in accordance with the line of characters being indicated in the record strip and is preferably set to arrest the repeat mechanism when the justification area of the line has been reached; thus the operator is relieved from the necessity of close attention, and when the repeat action is arrested it is only necessary to complete the line indications in the record strip by making the proper justification indications therein in the ordinary way.

Referring particularly to Figs. 1 and 4 of the drawings, it will be seen that a motor cylinder 16 is mounted in the base frame of the machine preferably by being fastened to the valve chest 17, and this cylinder is in communication through a pipe 18 with the cylinder 138 below its piston. The pipe 18 has a valve 19 interposed therein, and the valve stem 20 of the valve 19 is adapted to be manipulated to open and close the communication with the motor 16 for controlling the repeat action as will hereinafter appear. Piston 21 of the motor cylinder 16 is adapted to coöperate with a rocker preferably consisting of levers 22, journaled in supports 23 depending from the valve chest, said levers being connected at their rear ends by a bar 23 and at their forward ends by an upwardly extending bail 25 having its intermediate portion in the form of a bar 26 extending across the machine from side to side in rear of the inner ends of the valve controller bars 173. The bail 25 is adjustably mounted in the arms of the levers 22 by lock nuts 27, and the bar 24 of the rocker carries a shoe 46 with which the end of the piston 21 is adapted to coöperate to depress the rear end of the rocker whenever pressure is admitted to the cylinder 16 through the pipe 18. Reverse movement of the rocker is effected by means of a spring or springs 47, which spring holds the rocker normally in the position indicated in Fig. 1, with the piston 21 retracted.

In the arrangement illustrated the shoe 46 is rigidly mounted on the rocker and its downward movement is limited by an adjustable stop in the form of a screw 29 mounted in a hanger or bracket 28. Lock nuts 30 of ordinary construction may be provided for holding the stop screw in adjusted position.

These punch controllers 173 with which it is desired to effect the repeat action are at their inner ends provided with levers 31 adapted at their lower ends to coöperate with the horizontal bar 26 of the rocker and at their upper ends to coöperate with the proper valve stems 5, the inner ends of the controllers 173 to which the levers 31 are pivoted being preferably inclined or bent

downwardly out of the plane of the bodies of the bars as shown at 173^a, whereby such bars will not coöperate directly with the valve stems but only through the medium of the levers 31.

While all of the controllers 173 may be thus equipped, this is not essential, inasmuch as under certain circumstances it is found that the repeat action is desirable only in connection with certain keys, and in the machine illustrated the quad and leader keys and their valve bars 173 are equipped in the manner stated.

In Fig. 1, 32 indicates a quad key which is adapted to advance the controller bar 173 shown in full lines in that figure of the drawing, and when the bar is advanced with the rocker in its normal position, the lower end of the lever 31 is prevented from advancing by the bar 26 of the rocker, while the upper end of the lever is advanced to operate the valve stem 5, this operated position of the parts being shown in full lines in Fig. 6. If the valve controlling the admission of pressure to the motor 16 is closed, the release of the key 32 restores the controllers 173 and the valves controlled by the stems 5 to their normal positions and the indication made in the record strip is a single indication just as in the ordinary operation of the machine. If, however, the said valve 19 is open so that pressure is admitted to the motor 16, intermittently and in time with the operation of the punches, as will be the case because of the corresponding operation of the valve 146 in the well understood way, the piston 21 of the motor will be advanced under the action of the motive fluid and retracted under the action of the spring 47. The result of the advance of the piston 21 is to move the bar 26 of the rocker from the position shown in full lines to that shown in dotted lines in Fig. 6, with the result that even though the key 32 be held depressed, or in its operated position, the lever 31 is permitted to move on its pivotal support at the end of the bar 173 to the position shown in dotted lines in Fig. 6, and the valve controlled by the stems 5 will close. This operation is immediately followed by a reverse movement of the rocker under the influence of the spring, for the pressure in the motor is relieved when the cylinder 138 is put into communication with the exhaust. The reverse movement of the rocker again operates the lever 31 to open the valve 5 and these actions are continued just so long as the key 32 is held in its depressed or operated position and the valve 19 for admitting pressure is open.

The valve 19 is, in the preferred construction, normally held in closed position by a spring 35 connected with one end of the cross bar 36 on the valve stem, so that no repeat action will occur, but said valve is

adapted to be opened against the tension of the spring 35 by an operating member which is conveniently in the form of a repeat key 37 connected by a rod 38 with the cross bar 36 of the valve and preferably extending out through the front of the frame to bring the repeat key into convenient position for manipulation by the operator.

In the particular embodiment illustrated 10 the repeat key is adapted to be drawn outwardly or forwardly to open the valve, and in order that it may be retained in such position without requiring the operator to keep his hand on it, as well as to provide a means 15 whereby it may be automatically released to allow the valve of the repeat motor to close, a pawl or catch 39 is pivotally mounted on a bracket 40 at the front of the base frame in position to engage a shoulder 41 on the 20 repeat key, when the latter is drawn forwardly to the position indicated in Figs. 1 and 2. The catch 39 is preferably of such construction that it will automatically engage the shoulder 41 to hold the repeat key 25 in its operated position, and the release of the catch to permit the repeat key to return to its normal inoperative position may be effected either by hand or automatically under the control of the indicating mechanism 30 of the key board. A convenient arrangement and one which has proven in practice to be effective, embodies a bell crank lever 42 pivotally mounted in the support or bracket 40 and having one arm projecting over the 35 rear end of the catch 39, while its other arm projects up into proximity to the line scale rack 14 forming a finger piece 43 which may be moved by the operator's finger.

The end of the trip lever at 43 is adapted 40 to be moved into position to release the catch by a projection carried by the line scale rack, and in the simple embodiment of the invention illustrated, the line scale indicator 44 which projects from the side of the line 45 scale rack 14 is utilized as the stop or tripping device for the trip lever. When the line scale rack advances to the position shown in Fig. 3 the trip lever will have been moved, the catch 39 released, and the repeat 50 key restored to its normal inoperative position, arresting the functions of the repeat mechanism.

In operation, the key board is manipulated in the usual manner to produce the desired 55 character indications in the record strip, and when a point has been reached where a large number of characters of the same kind are to be indicated as, for example, in tabular work where there is a short 60 line or even a single word at the beginning of a line, and the balance of the line is filled by quads, the repeat key is operated in connection with the quad key, thereby starting the automatic action, to produce the desired 65 indications in succession in the record strip

with extreme rapidity. The rapidity of the repeat action is greater than it is possible to operate the key board by successive depressions of the key. When the action has continued to the desired point the repeat action 70 may be arrested by releasing the repeat key, or the character key, or it may be automatically arrested by the automatic tripping of the repeat key through the trip lever, as hereinbefore explained, whereupon the operator completes the line indications by operating the necessary justification keys or other character in the usual way.

Obviously, if the repeat mechanism is only used in connection with one or a small number 75 of keys in the key board, the repeat key valve may be left open or opened before beginning a line, inasmuch as the repeat motor will not be effective to manipulate any valves other than those of the keys in connection 80 with which the repeat mechanism is used. Without the controller 173 is advanced from the position shown in Fig. 1 to that shown in Fig. 6, the operation of the repeat mechanism will simply result in withdrawing the 85 bar 26 from in front of the lever 31 and again restoring the said bar to its normal position without operating the valve. In fact, the repeat key itself may be omitted, together with the valve in the connection 90 18, where the repeat mechanism is used only in connection with keys which are designed for repeat action whenever they are operated; thus, for example, the key board may have one of the duplicate quad keys arranged for 95 ordinary quading by successive manipulations of the key and the other for quading by operating the key and holding it in its operated position during the period it is desired that the repeat action shall be effective.

Having thus described my invention, what I claim as new and desire to secure by Letters Patent of the United States, is:

1. In a record strip composing machine 110 for producing characters for printing forms, the combination with designating keys, selectors for producing the desired indications in the record strip and connections intermediate the keys and selectors 115 whereby the selectors are operated, of an independent repeat motor, and means whereby said motor may be rendered effective to repeat the action of a key on its selector or selectors.

2. In a record strip composing machine 120 for producing characters for printing forms, the combination with designating keys, selectors for producing the desired indications in the record strip, motor mechanism and connections whereby the keys control the operation of the motor mechanism and selectors, of an independent repeat motor, and means whereby said repeat motor may be rendered effective to repeat 125 130

the action of a key on its selector or selectors.

3. In a record strip composing machine for producing characters for printing forms, the combination with selector mechanism for producing the desired indications in the record strip, motor mechanism for operating the selector mechanism, designating keys, and connections operated by the 10 depression of the designating keys to set in operation the motor mechanism of the selector or selectors for the character indication corresponding to the operated key, of an independent repeat motor, and means 15 whereby said repeat motor is rendered effective to cause the motor mechanism to repeat its action on a selector or selectors.

4. In a record strip composing machine for producing characters for printing forms, the combination with selector mechanism for producing the desired indications in the record strip, motor mechanism for operating the selector mechanism, designating keys, connections operated by the depression 20 of the designating keys to set in operation the motor mechanism of the selector or selectors for the character indication corresponding to the operated key, of a repeat motor independent of the selector motor and 25 designating keys, connections whereby said repeat motor will operate in timed relation to the selector mechanism, and means whereby said repeat motor is rendered effective to cause the selector motor mechanism to repeat its action on a designated selector or 30 selectors.

5. In an apparatus of the character described, the combination of selectors for producing the desired indications in a record strip, motor mechanism for the selectors, 40 designating keys for determining which selectors shall be operated, a repeat motor for causing the selector motor mechanism to repeat its action on the designated selector or 45 selectors, and connections intermediate the selector motor mechanism and repeat motor whereby they are caused to operate in timed relation.

6. In an apparatus of the character described, the combination of selectors for producing the desired indications in a record strip, motor mechanism for the selectors, designating keys for determining which selectors shall be operated, a repeat 50 motor for causing the selector motor mechanism to repeat its action on the designated selector, and a repeat key controlling the repeat motor whereby upon the operation of a designating key in conjunction with the 55 repeat key the designated indication will be repeated in the record strip.

7. In an apparatus of the character described, the combination of selectors for producing the desired indications in a record 60 strip, motor mechanism for the selectors,

designating keys for determining which selectors shall be operated, a repeat motor for causing the selector motor mechanism to repeat its action on the designated selectors, a repeat key controlling the repeat motor, 70 and means for locking the repeat key in its operated position, whereby upon the operation of a designating key its character indication will be repeated in the record strip.

8. In an apparatus of the character described, the combination of selectors for producing the desired indications in a record strip, motor mechanism for the selectors, designating keys for determining which selectors shall be operated, a repeat motor for 75 causing the selector motor mechanism to repeat its action on the designated selectors, a repeat key controlling the repeat motor, a catch for locking the repeat key in its operated position, and means whereby the 80 catch may be released and the repeat key restored to its inoperative position.

9. In an apparatus of the character described, the combination of selectors for producing the desired indications in a record 85 strip, motor mechanism for the selectors, designating keys for determining which selectors shall be operated, a repeat motor for causing the selector motor mechanism to repeat its action on the designated selectors, 90 a repeat key controlling the repeat motor, a catch for locking the repeat key in its operated position, and means responsive to the progressive movement of the mechanism in 95 the production of successive indications in 100 the record strip for releasing the repeat key to arrest the repeat action.

10. In an apparatus of the character described, the combination of selectors for producing the desired indications in a record 105 strip, motor mechanism for the selectors, designating keys for determining which selector shall be operated, a repeat motor for causing the selector motor mechanism to repeat its action on the designated selectors, 110 and means responsive to the progressive movement of the mechanism in the formation of successive indications in the record strip for arresting the action of the repeat motor.

11. In an apparatus of the character described, the combination of selectors for producing the desired indications in a record strip, motor mechanism for the selectors, designating keys for determining which selector shall be operated, a repeat motor for causing the selector motor mechanism to repeat its action on the designating selectors, 120 manually controlled means for inaugurating the action of the repeat motor, and means 125 responsive to the progressive movement of the mechanism in the formation of successive indications in the record strip for arresting the action of the repeat motor.

12. In an apparatus of the character de- 130

6
scribed, the combination with selectors for producing the desired indications in a record strip, a designating key and connections intermediate the key and selectors whereby 5 the operation of the key will cause selectors corresponding to the key to be operated to make a record indication, of a repeat motor coöoperating with said connections intermediate the key and selectors to repeat the action of the key on said selectors.

10 13. In an apparatus of the character described, the combination with selectors for producing the desired indications in a record strip, and a designating key, of connections intermediate the key and selectors whereby 15 selectors corresponding to the key will be operated to make a record indication embodying a reversely movable member, and a repeat motor controlling said member 20 whereby the operation of the key on the

selector may be repeated by the actuation of said reversely movable member by the repeat motor.

14. In an apparatus of the character described, the combination of selectors for producing the desired indications in a record strip, a designating key, an intermittently operating repeat motor, connections whereby the repeat motor is caused to operate in time with the selectors, and connections intermediate the designating key and selectors and intermediate the repeat motor and selectors, whereby the combined action of the key and repeat motor will cause the selectors to repeat their indication in the record strip. 25 30 35
